ELECTRICAL PLUG AND SOCKET STRUCTURE

Theodore Werner Wallschlaeger, Chicago, Ill., as
signor to Cinch Manufacturing Corporation,
Chicago, Ill., a corporation of Illinois

Application May 13, 1936, Serial No. 79,500

7 Claims. (CL 173—332)

My invention relates to improvements in a plug or like device for an electrical plug and socket connection and to installations of the same.

Referring to the drawing, which illustrates a preferred embodiment of my invention:—

Figure 1 is a side elevation of my electrical plug and socket installation;

Fig. 2 is a bottom plan view of the installation shown in Fig. 1 with a possible first position of my improved guide means shown in dotted lines;

Fig. 3 is a fragmentary section taken along the line 3—3 of Fig. 2;

Fig. 4 is a section similar to that of Fig. 3 showing the plug member of my installation withdrawn from electrical connection with the socket member and in a position one hundred and eighty degrees rotated from the engaging position with the socket;

Fig. 5 is a top plan view of the attaching part 20 of my plug member;

Fig. 6 is a bottom plan view of the attaching part of my plug member; and

Fig. 7 is a top plan view of the socket member of the installation.

An object of my invention is to provide a simple, yet efficient, means for guiding the prongs of a plug member into correct position for connection with the proper cooperating prong-receiving elements of a socket member.

Other objects of my invention will be apparent from an inspection of the drawing in which Figs. 1 and 2 represent a plug member 1 having an attaching part 2 carrying contact prongs which are in engagement with contact elements 3 of a socket member 4. A guide means 5 extends through the socket member 4 for reasons which will be hereinafter described.

Referring now in detail to the plug member of the installation, I have shown in Figs. 1, 3 and 4 a well known connector plug member comprising a cup-shaped part 6, which may be made of sheet metal or any other suitable material, having an open end to which is secured the attaching part of my plug member. The attaching part of my plug member, illustrated in Figs. 5 and 6, comprises a lower insulating plate 7 carrying a plurality of contact prongs 8 adapted for contact with cooperating terminals of the socket member of my installation. The contact prongs 8 preferably extend from the plate 7 in parallel relation one to another and are arranged in substantially circular relation within the outer periphery of the plate 7, as most clearly shown in Fig. 6. The relative length and transverse diameter of each of the prongs 8, in my preferred form,

are substantially the same. A second insulating plate 9 is disposed above the plate 7 with its peripheral outer edge, in my preferred form, disposed within the peripheral outer edge of the plate 7, as most clearly shown in Fig. 5. The plate 9 has a plurality of apertures 10 in alignment with the contact prongs 8.

In order to prevent the prongs 8 from being engaged with the wrong contact terminals of the socket member when electrical connection is made between the plug and socket members, I have provided a guide means 5 preferably made of metal and formed in a manner to provide a substantially rectangular-shaped portion 11 having opposed flat sides. The rectangular-shaped portion 11 extends beneath the plate 7 in the same direction as the prongs 8 to a point below the outermost ends of the prongs 8, as shown in Fig. 4. The portion 11 is disposed within the circle of the prongs 8 and has a pair of opposed longitudinal free edges in offset relation relative to the center of the circle (Figs. 4 and 6) for reasons which will be hereinafter more fully described. Shoulders 12 are formed at one end of the rectangular portion of the guide means 5 engaging the undersurface of the plate 7, and a shank 13 extends upwardly between the shoulders through the plates 7 and 9 in the manner shown in Figs. 3 and 4. The free end of the shank 13 is bifurcated so as to provide portions 14 engaging the upper surface of the plate 9. As a result of this construction, the plates 7 and 9 are maintained in secure assembly between the shoulders 12 of the guide means 5 and the bifurcated portions 14. The opposite end of the rectangular portion 11 from the shank 13, in my preferred form, is notched adjacent one longitudinal free edge so as to provide a shoulder 15 and an integral extending portion 16 of less width than that of the rectangular portion 11 (Figs. 3 and 4).

In securing my attaching part to the open end of the cup-shaped container 6, portions 17 of the material adjacent to the free end of the container are bent inwardly between the plates 7 and 9 so as to engage the undersurface of the plate 9, as most clearly shown in Figs. 3 and 4. As a result of this construction the insulating plate 9 is located within the cup-shaped container 6 and the plate 7 is disposed adjacent to the peripheral free edges of the container 6 and in close relation to the plate 9. In my preferred form, a portion 18 of the material adjacent to the free edge of the container 6 extends downwardly into a notch 19 provided in the peripheral free edge of the plate 7 for the purpose 55

of preventing relative rotation of the parts. The material of the container 6 at that end opposite the end to which the attaching part is secured has been extruded to provide an opening (not shown) and a neck 20 large enough on the inside to allow the entrance of a wire or group of wires into the container 6 for attachment to the prongs 8 carried by the plate 7. In general, the cooperation between the two parts and the construction are the same, as best illustrated and described in United States Letters Patent to Carl L. Knutson, No. 2,031,564, issued February 18, 1936.

The particular socket which I have chosen in my preferred installation has a relatively thin bottom plate 21 formed of insulating material having yieldable socket terminals arranged in substantially circular position about an aperture. The aperture comprises a substantially circular hole 22 which is located in the center of the ring of terminals and has a notch 23 on one side extending toward the circle of elements. While yieldable contact terminals of any suitable construction may be associated with the bottom plate 21, I have shown preferred contact members provided with tubular prong-receiving portions 24 and integral soldering lugs 25 extending beneath the plate 21 for the usual purpose. The socket member is also provided with a top plate 26 of insulating material having apertures 27 (Fig. 7) arranged in alignment with the tubular prong-receiving terminals 24 to permit the passage of the cooperating prongs of the plug member through the plate 26 into engagement with the socket terminals. An aperture is provided within the ring of the apertures 27 in alignment with the aperture within the ring of terminals 24 of the bottom plate 21 and shaped to provide a circular hole 28 which is located in the center of the ring of apertures and has a notch 29 on one side which extends toward the ring of apertures so that the aperture within the ring of the top plate conforms in shape as nearly as possible with the aperture within the ring of the bottom plate. The plates 21 and 26 are secured together by the rivets 30 and aligned apertures 31 are formed in the plates 21 and 26 and adapted to receive a rivet or other means for attaching the socket member to a supporting part.

In moving my plug member 1 into electrical connection with the socket member 4, the portion 16 at the free end of the guide means is inserted into the circular hole 28 located in the center of the ring of apertures of the top plate 26. When the portion 16 is first inserted into the hole, it is probable that the rectangular portion 11 will not align with the hole 28 and the notch 29 so that it may be passed completely therethrough, but instead will lie substantially across the hole 28 in the manner shown in dotted lines in Fig. 2. When the portion 16 is in this position, the shoulder 15 engages the material surrounding the hole 28 and, as the width of the portion 16 is substantially equal to the diameter of the hole, it may be rotated therein until the shoulder 15 is in alignment with the notch 29, at which time the rectangular-shaped portion 11 of the guide means may be passed through the top and bottom plates of the socket member. As a result of my preferred construction, in which one longitudinal edge of the rectangular-shaped portion 11 and the cooperating notch 29 of the socket plate are offset relative to the center of the circle of contact prongs 8 (Figs. 4 and

6) and the apertures 27 respectively, it is impossible to move the prongs into engagement with the cooperating prong-receiving portions 24 of the socket member unless the rectangular-shaped portion 11 is passed through the centrally disposed apertures of the socket plates with the shoulder 15 in proper alignment and relation with the notches 29 and 23 of the respective apertures. It will be seen, therefore, that if the longitudinal edge of the portion 11, opposed to that edge adjacent the shoulder portion 15, is aligned with the notches 29 and 23 (Fig. 4) it will be impossible to align the contact prongs 8 with the apertures 27 of the top plate 26 even though the plug member carries an equal number of prongs spaced equally one from another and the plate 26 an equal number of apertures 27 arranged to receive the prongs of the plug member. The portion 11 can only enter until the prongs 8 touch the socket. Thus it will be necessary for the operator to remove the portion 11 and start over until it is rotated to a position when it will enter the socket, as shown in Fig. 3.

Although I have illustrated and described a preferred embodiment of my invention, I do not wish to be limited thereby because the scope of my invention is best set forth by the following claims.

I claim:

1. An electrical connection comprising, in combination, cooperating plug and socket members, said plug member including a housing, a plurality of contact prongs extending from one end thereof and disposed in substantially circular relation, and a flat guide means disposed in off-center relation to the circle of said prongs, said guide means having one end secured within said housing and the other end extending in the same direction as said prongs said last mentioned end having a notch providing a shoulder, said socket having an elongated guide-receiving opening in certain positions of the plug relative to the socket, said guide means adapted to extend completely through a cooperating aperture of a socket device only when said contact prongs are in registry with the proper prong-receiving elements of said socket device.

2. An electrical connection comprising, in combination, cooperating plug and socket members, said plug member including a housing, a plurality of contact prongs extending from one end thereof, and a guide means extending from said last-mentioned end of said housing in the direction of said prongs, said guide means having a notch at its free end providing a shoulder, said socket having an elongated guide-receiving opening so that said shoulder will rest against an edge of the opening in certain positions of the plug relative to the socket, said guide means adapted to extend completely through a cooperating aperture of a socket device only when said contact prongs are in registry with the proper prong-receiving elements of said socket device.

3. A plug for electrical connections including a container having an open end, a plurality of insulating plates in fixed assembly with said container at said open end, a plurality of contact prongs carried by at least one of said plates and arranged in substantially circular relation, and a one-piece metal guide means carried by said plates and disposed within the circle of said prongs, said guide means including a body portion having opposed flat sides extending from said plates in the same direction as said prongs to a point beneath said prongs, said body portion

- having shoulders at one end engaging the outer surface of one of said plates and a shank portion extending through at least one of said plates, said shank having a bifurcated portion engaging the inner surface of said plate whereby said body portion is secured thereto, and said body portion having a notch at the other end presenting a shoulder for the purpose described.
4. A plug for electrical connections including a container having an open end, a pair of insulating plates in fixed assembly with said container at said open end, a plurality of contact prongs carried by at least one of said plates and arranged in substantially circular relation, and a one-piece guide means carried by at least one of said plates and disposed within the circle of said prongs and in off-center relation thereto, one end of said guide means having portions in fastened engagement with at least one of said plates whereby said guide is secured thereto, the other end of said guide extending from said plate in the direction of said prongs and adapted to extend completely through a cooperating aperture of a socket device only when each of said contact prongs is in registry with the proper prong-receiving element of said socket device, said other end having a notch adjacent one longitudinal free edge of the guide providing a shoulder and an extending portion for the purpose described.
5. A plug for electrical connections including a container having an open end, a pair of insulating plates assembled with said container at said open end, one of said plates secured within said container, the other of said plates located outside said container and in close relation to said first plate, a plurality of contact prongs carried by at least one of said plates, and a guide means secured to said plates and extending therefrom in the direction of said prongs for cooperating with a socket device in a way to insure registration of each of said prongs with the proper prong-receiving terminal of said socket device, said guide having means engaging a surface of said outside plate and a surface of said other plate for securing said outside plate to the other of said plates.
6. An electrical connection comprising, in combination, plug and socket members, said plug member having a plurality of contact prongs disposed in substantially circular relation and extending from one end thereof, and a flat guide means disposed in off-center relation to the circle of said prongs, said guide means extending in the same direction as said prongs, and said socket member carrying a plurality of prong-receiving terminals disposed in substantially circular relation, said socket member providing an aperture having an elongation on one side disposed in off-center relation to the circle of said wire-receiving terminals, said guide means extending through said aperture and said elongation only when each of said contact prongs is in proper registry relative to said respective prong-receiving terminal.
7. An electrical connection comprising, in combination, plug and socket members, said plug member having a plurality of contact prongs disposed in substantially circular relation and extending from one end thereof, and a flat guide means disposed in off-center relation to the circle of said prongs, said guide means extending in the same direction as said prongs, and said socket member carrying a plurality of prong-receiving terminals disposed in substantially circular relation, said socket member providing an aperture having an elongation on one side disposed in off-center relation to the circle of said wire-receiving terminals, said guide means extending through said aperture and said elongation only when each of said contact prongs is in proper registry relative to said respective prong-receiving terminal, and said guide means having a notch at its free end adjacent to one longitudinal edge thereof providing a shoulder and an extension of said guide means permitting relative rotation of the parts before proper registry.

THEODORE WERNER WALLSCHLAEGER.
